UNITED STATES PATENT OFFICE.

WILLIAM SCHMACHTENBERG, OF NEW YORK, N. Y.

DESIGN FOR A HANDLE FOR KNIVES.

SPECIFICATION forming part of Design No. 26,723, dated March 9, 1897.

Application filed January 18, 1897. Serial No. 619,686. Term of patent 3½ years.

To all whom it may concern:

Be it known that I, WILLIAM SCHMACHTENBERG, of New York, in the county and State of New York, have invented and produced a new and original Design for a Metallic Handle for Jackknives, of which the following is a full, clear, and exact description.

Reference is to be had to the accompanying drawing, forming a part of this specification, in which the figure is a perspective view of a jackknife, showing my design.

The leading feature of my design consists in the dull-finished faces A of the body of the handle and the brightly-polished ends A' A'' of the handle.

Other features of the design consist in the tapering handle, tapered from the butt-end A² to the polished end A', and in the transverse recess A³, of approximately crescent shape, at the front edge of the handle at the 20 butt-end, and the outwardly-beveled surface A⁴, brightly polished in contrast to the adjoining dull face A.

I claim—

The design for a metallic handle for jack- 25 knives as herein shown and described.

WILLIAM SCHMACHTENBERG.
